[57] CLAIM

The ornamental design for an apparatus for manufacturing porcelain dolls, as shown and described.

DESCRIPTION

FIG. 1 is a front elevational view of an apparatus for manufacturing porcelain dolls showing my new design; FIG. 2 is a right side elevational view of the apparatus shown in FIG. 1; the left side elevational view is identical to the right side elevational view.

FIG. 3 is a rear elevational view of the apparatus shown in FIG. 1.

FIG. 4 is a top view of the apparatus shown in FIG. 1; and, FIG. 5 is a bottom view of the apparatus shown in FIG. 1.
